UNITED STATES PATENT OFFICE

160,313

PLATFORM FOR SILVERWARE

Paul M. Fuller, Oneida, N. Y.

Application April 13, 1949, Serial No. 1,949

Term of patent 3½ years

(Cl. D44—29)

To all whom it may concern:

Be it known that I, Paul M. Fuller, a citizen of the United States, residing at Oneida, in the county of Madison and State of New York, have invented a new, original, and ornamental Design for Platform for Silverware, of which the following is a specification, reference being had to the accompanying drawing, forming a part thereof.

The figure is a perspective view of a platform for silverware, showing my new design.

I claim:

The ornamental design for a platform for silverware, substantially as shown.

PAUL M. FULLER.
